UNITED STATES PATENT OFFICE.

OTTO W. SCHAUML, OF PHILADELPHIA, PENNSYLVANIA.

DESIGN FOR A LATHE-PLATE.

SPECIFICATION forming part of Design No. 30,350, dated March 14, 1899.

Application filed February 4, 1899. Serial No. 704,584. Term of patent 14 years.

To all whom it may concern:

- Be it known that I, OTTO W. SCHAUML, a citizen of the United States, residing at Philadelphia, in the State of Pennsylvania, have
5 invented and produced a new and original Design for Lathe-Plates for Looms, of which the following is a specification, reference being had to the accompanying drawings, forming a part thereof.
- 10 This invention consists in a design for a lathe-plate—that is to say, a device commonly known as “lathe-plates”—employed for securely sustaining shuttle-blocks in position upon the batten of a loom and for affording, 15 with said shuttle-blocks, supports for the reeds.
- The design is clearly illustrated in the accompanying drawings, wherein—
- 15 Figures 1 and 2 are front and back views, respectively. Figs. 3 and 4 are longitudinal sectional views on the lines *w w* and *x x*, respectively, in Fig. 2; and Figs. 5 and 6 are transverse sectional views on the lines *y y* and 20 *z z*, respectively, in Fig. 2.
- 25 The essential features of my design consist in a pair of vertical or upright and parallel

bars *a* and *b*, which are connected at their upper ends by a horizontal bar *c* and approximately midway their length by another horizontal bar *d*, disposed substantially parallel 30 to said bar *c*. Between the vertical bars the two horizontal bars bulge somewhat outwardly, thus forming in their rear faces longitudinal recesses or depressions *e* and *f*.

The horizontal bar *d* is provided along its 35 lower edge with a rearwardly-projecting rib *g*, which, with the recess *f*, forms an elongated socket.

It should be remarked that the recesses *e* and *f* approximate in length. 40

Having thus fully described my invention, what I claim as new, and desire to secure by Letters Patent, is—

The design for a lathe-plate substantially as herein shown and described. 45

In testimony that I claim the foregoing I have hereunto set my hand this 31st day of January, 1899.

OTTO W. SCHAUML.
